UNITED STATES PATENT OFFICE.

ROBERT DE POLO, OF CONNELLSVILLE, PENNSYLVANIA.

HEATER.

1,245,885.

Specification of Letters Patent.

Patented Nov. 6, 1917.

Application filed March 29, 1917. Serial No. 158,258.

To all whom it may concern:

Be it known that I, ROBERT DE POLO, a citizen of the United States, residing at Connellsville, in the county of Fayette, State 5 of Pennsylvania, have invented a new and useful Heater; and I do hereby declare the following to be a full, clear, and exact description of the invention, such as will enable others skilled in the art to which it applies 10 to make and use the same.

This invention relates to an improved heater and system, and an object of the invention is to provide an apparatus of this kind found particularly useful and advantageous for heating railway stations, country schools, and country and town offices, and various other buildings.

A further object of the invention is to provide a heater and system so constructed 20 and installed as to do away with a great deal of heat, smoke and the like that have been heretofore tolerated.

A further object of the invention is to provide a heater constructed of bricks or 25 fire brick or the like, and to protrude out about a foot from the wall, more or less, and covered with ornamental tiles, making a finished structure (the exterior appearance of which to more or less resemble the 30 old German porcelain stove) so as to receive products of combustion from a suitable stove a remote distance from the heater, whereby the bricks and the like become red hot, thereby generating and radiating heat.

A further object of the invention is to provide an improved heater in connection 35 with which a stove of any suitable construction for burning any kind of fuel, coal or trash and located at any remote distance 40 from the heater, may be employed.

A further object of the invention is to provide a heater having a system of heating flues, the heat from which will cause the bricks of the heater to become red hot, 45 thereby radiating sufficient heat to heat the cold air in the cold air passages.

A further object of the invention is to provide a heat chamber extending over the heat flues and provided with an opening 50 communicating with the interior of the room, there being a damper to control the heat into the interior of the room.

In practical fields, the details of construction may necessitate alterations falling within 55 the scope of what is claimed.

The invention comprises further features and combination of parts, as hereinafter set forth, shown in the drawings and claimed.

In the drawings:—

Figure 1 is a view in perspective of the 60 improved heater, constructed in accordance with the invention.

Fig. 2 is a vertical sectional view on line 2—2 of Fig. 1.

Fig. 3 is a transverse sectional view on 65 line 3—3 of Fig. 2.

Fig. 4 is a transverse sectional view on line 4—4 of Fig. 2.

Fig. 5 is a vertical sectional view on line 5—5 of Fig. 2.

Fig. 6 is a vertical sectional view showing parts in elevation of another form of heater used in connection with an open grate.

Fig. 7 is a cross sectional view on line 75 7—7 of Fig. 6.

Referring more especially to the drawings, 1 designates the casing of the heater, the inner portions of the outer walls and the various interior walls of which may be 80 constructed of suitable fire brick or other refractory material, in order to become heated, and insure the radiation of the heat. The outer portion of the casing of the heater may be covered with any suitable tile, as 85 shown at 2 in Fig. 1, in order to present a neat outer appearance. This heater is designed to be built out into the room any suitable distance. Further, the casing may be of any conventional shape or configuration, preferably rectangular, and is provided with a plurality of flues 3, 4, 5 and 6, which are divided by the intersecting walls 7 and 8 and 9 and 10. A suitable flue or pipe 11 extends from a conventional form of stove 95 12, and enters and communicates with the flue 3 of the heater, so as to carry the heat or products of combustion from the stove into said passage or flue 3. This flue or passage 3 communicates with the flue or 100 passage 4 by way of the port or opening 13 over the top of the wall or division 8. The flue or passage 4 communicates with the flue or passage 5 by way of the port or opening 14, which extends under the wall 9. The flue 5 communicates with the flue 6 by way of the port or opening 15 at the top of the wall 10. It is to be noted that the products of combustion or heat from the stove 12 pass through the pipe or flue 11 and through 110

the several flues 3 to 6, inclusive, and pass out through the flue or pipe 16 to the exterior atmosphere. As the products of combustion take this course, the walls of the 5 flues 3 to 6, inclusive (which are constructed of any suitable refractory material) become highly heated, in fact, substantially red hot; therefore, heat radiates from the casing of the heater, heating the interior of the room, 10 as well as radiating heat into the heat chamber 17, the greater portion of which overlies the upper parts of said flues 3 to 6, inclusive. However, a wall 18 divides the heat chamber 17 from the upper end of the flues 3 to 15 6, inclusive. The heat chamber 17 has a downwardly extending part 18^a, there being an opening 19 in one of the side walls of the casing of the heater, so that heat from the chamber 17 may pass into the interior of 20 the room. A suitable rod 20 is mounted in bearings of the casing of the heater, and extends transversely of the portion 18^a of the chamber 17. One end of this rod is provided with a handle 21, whereby the rod 25 may be rotated. Mounted on and movable with the rod is an elongated damper 22, and when it is desired to confine the heat in the chamber 17, the damper 22 is closed, and in this case, the heat from the chamber 17 may 30 pass off through the pipes or flues 23, which may convey the heat to any suitable location, in order to be employed for heating other rooms. These pipes or flues 23 are provided with dampers 24 for controlling 35 the heat. Additional pipes or flues, similar to 23, may be provided for communication with the chamber 17. However, the number of pipes 23 depends upon the number of rooms that may be contained in the building. If desired each of the pipes 23 may 40 merge into branch pipes, which may extend to other rooms, each to have a damper to control the heat in its passage. The damper 22 may be thrown open, which will permit the heat in the chamber 17 to pass out 45 through the opening 19, into the room, in which the heater is arranged. A little below the opening 19, and across the lower part of the portion 18^a of the chamber 17, 50 a division wall 25 connects the outer wall 26 of the casing and the wall 27. This wall 25 is arranged or constructed to provide a pocket or water container 28, so that the heat that is allowed to pass from the chamber 17 through the opening 19 into the room 55 may absorb the requisite moisture. At the inner portions of the walls 7, 8, 9 and 10, where they intersect, a cold air flue 29 is provided. The lower portion 30 of the cold 60 air flue 29 is divided off from the upper portion 31 of said flue, by means of the wall 32. Upon the examination of the drawings, it is to be observed that cold air flues 33, 34, 35 and 36 are formed between the walls 7, 8, 65 9, and 10 respectively. The lower portion

30 of the flue 31 communicates with said flues 33 to 36, inclusive, by way of the ports 37. The upper portion 31 of the flue 29 communicates with the cold air flues 33 to 36, inclusive, by way of the ports 38. A 70 suitable cold air pipe 39 (which may receive air from any suitable source, not shown) connects to the lower part of the casing of the heater, in order to communicate with the lower part 30 of the cold air 75 flue 29. In this way air from any suitable source passes into the several cold air flues 33 to 36, inclusive, and passes upwardly through said flues 33 to 36 and through the ports 38, and through the upper part 31 of 80 the flue 29, and out through the pipe or flue 40. This cold air, in passing through the flues 33 to 36, is baffled by the baffle members 41, which are arranged in the several flues 33 to 36. The baffle members are 85 arranged in staggered relation and to overlie each other; hence, it will be seen that by baffling the cold air in this manner, the air is retarded and at the same time becomes heated, and may be carried off through the 90 pipe or flue 40, for heating purposes. Moreover, the cold air, as it is baffled and heated, when passing through the flues 33 to 36, has a tendency to modify the intense heat of the casing of the heater. By means of the damper 42, the outlet of the air through the flue or pipe 40 may be controlled. In the lower part of the flue 3 a fire pot 43 is constructed, and which may be of any conventional form, and the grate 44 of this fire pot 100 may be supported in any suitable manner, for instance, upon the flange 45 of the wall of the fire pot, so as to rock. Projecting from the grate 44 is a projection 46 extending through a slot 47 a little below the door 105 or closure 48 of the heater, and is provided with a handle 49. By imparting a backward and forward movement to the handle 49, the grate may be agitated, in order to loosen the ashes from the bed of coals supported in the pot. The door or closure 48 closes the opening 50, through which coal or the like may be put into the fire pot 43, and which may be used only when the stove 12 is dispensed with. When dispensing with 110 the stove 12, the ashes or the like may pass through the pipe or flue 11 down into a suitable receptacle in the cellar, not shown. A cross connecting flue 51 connects the flues 11 and 16 and is provided with a damper 115 52, so that the heat may be carried off through the flue 16, by opening the damper 52 and closing the damper 53, so as to cool off the heater. Connected to the lower wall 120 of the heater and in communication with the lower parts of the flues 4 and 5 are pipes 54, the lower ends of which are provided with caps or closures 55, by the removal of which caps, the soot and the like may be removed. Embedded in the upper portion of the front 125 130

wall of the heater is a suitable thermometer 56, for registering the intensity of the heat of the heater.

In Figs. 6 and 7, a heater 60 is shown, and 5 is designed to be constructed of any suitable refractory material, and is provided with four flues 61, 62, 63 and 64. This heater is constructed adjacent to one side of a wall 65, the other side of which wall is provided 10 with the usual form of open fire place 66 provided with an open fire grate 67. This open fire place is substantially arched, and has its side walls 68 provided with ports of communication with the side passages 70, 15 which are provided with suitable dampers 71 and 72, which are disposed above the ports 68. These passages 70 merge into a single passage 73 of the chimney 74. One of the passages 70 has a port of communication 20 through the wall 65 with the flue 61, which is in communication with the flue 62 by way of the port 76 under the lower end of the partition 77. The flue 62 is in turn in communication with the flue 63 by way 25 of the port 78, and the flue 63 communicates with the flue 64 by way of the port 79. The upper end of the flue 64 communicates with the flue 73 of the chimney by way of the port 80, that is, above the damper 71. It 30 will be seen that the heat arising from the fire in the grate 67, provided the damper 71 is closed, will pass through the ports 68 and 75 into the flue 61 and thence into the several other flues 62, 63 and 64 and up through the 35 flue of the chimney by way of the port 80. If the damper 72 is closed, likewise the damper 71, all the heat will follow such a course, as above stated. However, if the damper 72 is open or partially open, a pro- 40 portion of the amount of heat will pass through the flue having the damper 72, thereby lessening the amount of heat that will pass through the passage having the damper 71, provided said damper 71 is 45 closed. Extending down from the lower wall or the bottom of the heater shown in Figs. 6 and 7 and communicating with the lower ends of the flues 61 to 64, inclusive, are pipes 82 having caps 83, which may be 50 removed for cleaning the soot and the like from the flues.

This present invention is an improvement over the heating system attachment for ranges of Robert De Polo, whose application 55 was filed June 30, 1916, and became patented December 12, 1916, Patent No. 1,208,300.

The invention having been set forth, what is claimed as new and useful, is:

1. A heater, comprising a casing con- 60 structed from refractory material, said casing having a heat chamber in its upper part and provided with a plurality of vertical

flues below said heat chamber, said flues being in communication at their alternate ends, thereby forming an undulated passage, 65 through which products of combustion from the heat generator may pass, whereby the refractory material may become heated and radiate heat into the heat chamber, and means for carrying off the heat from the 70 heat chamber, said heat chamber having a water container and an opening to allow the heat to enter a room.

2. A heater, comprising a casing constructed of refractory material, said casing 75 having a heat chamber in its upper part and provided with a plurality of vertical flues below said heat chamber, said flues being in communication at their alternate ends, thereby forming an undulated passage, 80 through which products of combustion from the heat generator may pass whereby the refractory material may become heated and radiate heat into the heat chamber, intersecting walls dividing and separating said 85 vertical flues, and where said walls intersect in the center of the casing being provided with a vertical cold air flue, and a partition dividing the lower part of the cold air flue from the upper part, said intersecting walls 90 being hollow and provided with cold air flues and being in communication with the upper and lower parts of the first cold air flue.

3. A heater, comprising a casing con- 95 structed of refractory material, said casing having a heat chamber in its upper part and provided with a plurality of vertical flues below said heat chamber, said flues being in communication at their alternate ends, thereby forming an undulated passage, through 100 which products of combustion from the heat generator may pass whereby the refractory material may become heated and radiate heat into the heat chamber, intersecting walls dividing and separating said vertical flues, and where said walls intersect in the center of the casing being provided with a vertical cold air flue, a partition dividing 105 the lower part of the cold air flue from the upper part, said intersecting walls having cold air flues in communication with the upper and lower parts of the first cold air flue, and baffle members arranged in the second cold air flues and in staggered relation, 110 whereby the cold air passing therethrough will be baffled.

In testimony whereof I have signed my name to this specification in the presence of two subscribing witnesses.

ROBERT DE POLO.
